United States Patent

Des. 238,643

Patented Feb. 3, 1976

238,643

TABLE

Elliot J. Binzen, 45 W. 11th St.,
New York, N.Y. 10011

Filed Nov. 27, 1972, Ser. No. 309,951

Term of patent 14 years

Int. Cl. D6—03

U.S. Cl. D6—177

FIG. 1

FIG. 2

FIG. 3

FIG. 4

FIG. 1 is a top plan view of the design of a second embodiment of a table;

FIG. 2 is a side elevational view from either side thereof;

FIG. 3 is a bottom plan view thereof; and

FIG. 4 is a front elevational view from either end thereof.

I claim:

The ornamental design for a table, as shown and described.
